UNITED STATES PATENT OFFICE.

STANLEY W. NICHOLSON, OF TOLEDO, OHIO, ASSIGNOR TO THE DURA COMPANY, OF TOLEDO, OHIO, A CORPORATION OF DELAWARE.

WINDOW-CONTROL MECHANISM.

Application filed May 22, 1922. Serial No. 562,871.

To all whom it may concern:

Be it known that I, STANLEY W. NICHOLSON, a citizen of the United States of America, residing at Toledo, in the county 5 of Lucas and State of Ohio, have invented certain new and useful Improvements in Window-Control Mechanism, of which the following is a specification, reference being had therein to the accompanying drawings.

This invention relates to window control mechanism and more particularly to control devices for the sliding windows of vehicles.

The invention consists in the structural features and arrangement of parts herein- 15 after fully described and illustrated in the accompanying drawings, wherein:—

Figure 1 is an interior view of an automobile door equipped with the improved mechanism;

Figure 2 is a view showing said mechanism as in Figure 1 but to an enlarged scale.

Figure 3 is a vertical cross section on line 3—3 of Figure 2;

Figure 4 is a cross section on line 4—4 25 of Figure 2;

In these views the reference character A designates an automobile door having in its upper portion the window opening B and provided with a closure for said opening 30 having the nature of a vertically sliding glass plate C. The lower portion of said door is formed with a well or chamber D into which said window member is lowered in its open positions. Within the chamber

D is arranged a counterbalance arm E pivoted at E' upon one of the uprights A' of the door and carrying at its free end a roller E' which is urged into constant contact with the lower edge of the plate C by a coil 40 spring F. G is a control rod for the closure C attached to the latter adjacent the lower edge thereof and upwardly extending adjacent the uprights A' so as to be accessible. Said rod is provided upon its upper end 45 with a handle H which is accessible within the opening B in all positions of said closure.

It is desired to utilize the rod G as a latch control element as well as an actuating member for the plate C and to this end there is 50 secured to one extremity of the customary channel I engaging the bottom edge of said plate a bracket J formed with a bearing K wherein, the lower end of said rod is journaled. Relative vertical movement between 55 the rod G and closure may be prevented by

providing upon said rod any suitable abutments coacting with the bearing K, as for example the nuts K' above and below said bearing. Said rod is integrally formed with a rib L, wherein is formed a series of notches 60 M which through rocking of the rod may be selectively engaged with a tooth member N mounted upon the uprights A', whereby the closure may be held in substantially any desired position of vertical adjustment. 65 A spring O coiled upon the lower end of said rod coacts with the bracket J to urge a rotation of the rod G, such as to normally engage the tooth N by one of the notches M of said rod. Rocking the handle H away 70 from the plate C from one to the other of the dash line positions shown in Figure 4 serves to unlatch the closure and a subsequent upward or downward pressure upon said handle effects the desired vertical shift- 75 ing of the closure.

It is preferred to dispose the rod G within a tubular metal trim stick P which is mounted upon the uprights A' within the opening B being secured in place by screws 80 P' or other suitable means. Said trim stick is slotted, as indicated at R, from end to end to permit the handle H to project and to coact the necessary angular and vertical movement. In the disclosed embodiment 85 of the invention the tooth N has the nature of a tongue struck out from the lower end of said trim stick, as is best seen in Figure 4.

The trim stick P in addition to concealing the control rod G functions also to some extent as a guide member for said rod.

What I claim as my invention is:—

1. In a window control mechanism, the combination with a sliding closure for a 95 window opening, of a control rod for said closure extending upon the latter in the direction of movement thereof and rotative to exercise a latch function, a latch element carried by said rod substantially co-extensive therewith and a fixed latch element engageable by said latch member through rocking of said rod.

2. In a window control mechanism, the combination with a sliding closure for a 105 window opening, of a control rod extending upon said closure in the direction of movement and rotative upon the closure to exercise a latch function, a rib integral with said rod and substantially co-extensive 110

- therewith, notched to form a latch member and a stationary latch element selectively engageable by the notches of said rib through rotation of the rod.
- 5 3. In a window control mechanism, the combination with a sliding closure for a window opening, and a chamber receiving said closure in its open positions, of a control member for said closure carried thereby 10 and elongated thereupon in the direction of travel thereof to be accessible within said opening in all positions of said closure, and latch means upon said control member substantially co-extensive therewith, and a co- 15 acting stationary latch member disposed within said chamber.
4. In a window control mechanism, a member having a window opening, a sliding closure for said opening, a chamber adjacent 20 said opening receiving said closure in the open positions thereof, a latch member within said chamber stationary relative to said closure, and a latch member upon the closure rotatively engageable with said stationary latch member and elongated in the 25 direction of travel of the closure for selective engagement with the stationary latch member in a plurality of positions of the closure.
- 30 5. In a window control mechanism, the combination with a sliding closure for a
- window opening, of a control rod extending upon said closure in the direction of travel thereof, said rod being rotatively mounted and notched to exercise a latch function in a plurality of positions, and a coacting stationary latch element.
6. In a window control mechanism, the combination with a sliding closure for a window opening, of a control rod extending upon said closure in the direction of travel thereof, said rod being notched and rotatively mounted to exercise a latch function in a plurality of positions, a co-acting stationary latch element, and means resiliently 45 acting upon said rod to urge engagement thereof with said stationary element.
7. In a window control mechanism, the combination with a sliding closure for a window opening, of a control rod for said closure extending upon the latter in the direction of movement thereof and rotative to exercise a latch function, a latch element carried by said rod substantially co-extensive therewith, a fixed latch element engageable by said latch element through locking of said rod, and means resiliently acting upon said rod urging the same rotatively into latch engagement with the fixed latch element.

In testimony whereof I affix my signature.
STANLEY W. NICHOLSON.
